UNITED STATES PATENT OFFICE.

GEORGE E. PITTS, OF WARWICK, NEW YORK.

HANDLE FOR MILK-CANS, &c.

No. 830,002.

Specification of Letters Patent.

Patented Sept. 4, 1906.

Application filed January 14, 1905. Serial No. 241,160.

To all whom it may concern:

Be it known that I, GEORGE E. PITTS, a citizen of the United States, residing at Warwick, in the county of Orange and State of New York, have invented a new and useful Handle for Milk-Cans, &c., of which the following is a specification.

My invention relates to certain new and useful improvements in milk-cans, and has for its object to provide a handle so constructed that all liability of the handle pulling off is prevented.

Another object of my invention is to provide a milk-can surrounded by a band carrying the handles, so that all danger of the handle pulling off accidentally after being put in place is prevented, and at the same time forming a protection to the can so that the cans will not become dented, as now is the case when they are shipped.

Another object of my invention is to provide a handle in connection with the can, formed of two members hinged together so that it can be easily and quickly removed when desired.

With these objects in view the invention consists of the novel features of construction and combination of parts hereinafter fully described, and pointed out in the claims.

In the drawings forming a part of this specification, Figure 1 is a perspective view of the can. Fig. 2 is a section of the lug carried by the hoop, showing the handle attached, partly broken away, so as to show the locking-bolt. Fig. 3 is a sectional view taken on the line 3 3 of Fig. 2. Fig. 4 is a perspective view of the handle detached. Fig. 5 is a detail view of the band, hoop, and lug.

Referring to the drawings, 1 designates the can of the ordinary construction, to the upper end of which is secured a band 2, having a hoop 2^a secured to the upper edge of the band, so as to relieve the solder over the band and to form a protection for the cans so as to prevent them from being dented by bumping up against one another when being shipped, and by shrinking this hoop on the band it makes it almost impossible for the band to be pulled off. To the hoop 2^a at opposite sides are secured lugs 3, having openings 4 formed therein and an upwardly-extending flap 3^a, adapted to be secured to the inclined top of the can. A transverse groove

is formed in the flap for the purpose herein-after described. The handle I prefer to use is constructed of two members 6, perforated at their ends, one of said members being forked and the other flattened, adapted to fit in said forked end and to be secured therein by a pin 9. The other end of the members are bent inwardly, forming lugs 5, adapted to extend to the opening in the lugs and to be securely locked therein by a bolt 7 passing through the openings 8, adjacent the end of the members 6.

From the foregoing description it will be seen that I have formed a very simple and cheap handle and one in which the handle can be turned up on the inclined top so that it will not be in the way when being shipped.

Having thus fully described my invention, what I claim as new, and desire to secure by Letters Patent, is—

1. The combination with a can, of a band secured to said can, a hoop secured on said band provided with perforated lugs, a handle formed in two parts hinged together, inwardly-projecting lugs formed on said handle and means for holding the lugs of the handle in the perforated ears of the hoop for the purpose described.

2. The combination with a can, of a hoop provided with perforated lugs secured to said can, a handle formed in two parts hinged together, lugs formed on said handle, openings formed in the parts of the handle, and a bolt adapted to pass through the openings in the handle and lock the lugs in the perforated ears of the hoop, for the purpose described.

3. The combination with a can, of a band secured to said can, a hoop pivoted with oppositely-arranged perforated lugs secured to the can over said band, a handle formed of two parts hinged together, provided with inwardly-projecting lugs at their ends, openings formed in the parts of the handle in alignment with each other, and a bolt adapted to pass through the openings in the handle and lock the lugs of the handle in the perforated lugs of the hoop, for the purpose described.

4. The combination with a can, of a band secured to the upper edge of said can, a hoop provided with apertured lugs having an upwardly-extending flap secured on said band and can and a separable handle secured in said lugs, for the purpose described.

5. The combination with a can, having an

inclined top, of a band secured to the upper edge of said can, a hoop secured on said band, apertured lugs secured on said hoop provided with an upwardly-extending flap secured to the inclined top and a separable handle provided with lugs secured in said apertured lugs of the hoop, for the purpose described.

In testimony whereof I have signed my name to this specification in the presence of 10 two subscribing witnesses.

GEORGE E. PITTS.
